CLAIM

We claim the ornamental design for a disposable diaper, as shown and described.

DESCRIPTION

FIG. 1 is a front perspective view of the first embodiment of a disposable diaper showing our new design.

FIG. 2 is a rear perspective view thereof;

FIG. 3 is a front view thereof;

FIG. 4 is a rear view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged fragmentary view defined by line 9 in FIG. 1;

FIG. 10 is an enlarged fragmentary view defined by line 10 in FIG. 3;

FIG. 11 is an enlarged fragmentary view defined by line 11 in FIG. 7;

FIG. 12 is an enlarged fragmentary view defined by line 12 in FIG. 10 showing the inside of the waist band in an open condition;

FIG. 13 is an enlarged cross-sectional view taken along line 13-13 in FIG. 10;

FIG. 14 is a front perspective view of the second embodiment of a disposable diaper showing our new design.

FIG. 15 is a rear perspective view thereof;

FIG. 16 is a front view thereof;

FIG. 17 is a rear view thereof;

FIG. 18 is a left side elevational view thereof;

FIG. 19 is a right side elevational view thereof;

FIG. 20 is a top plan view thereof;

FIG. 21 is a bottom plan view thereof;

FIG. 22 is an enlarged fragmentary view defined by line 22 in FIG. 14;

FIG. 23 is an enlarged fragmentary view defined by line 23 in FIG. 16;

(Continued)

9

FIG. 24 is an enlarged fragmentary view defined by line 24 in FIG. 20;

FIG. 25 is an enlarged fragmentary view defined by line 25 in FIG. 23 showing the waist band being turn over thereof; and,

FIG. 26 is an enlarged cross-sectional view taken along line 26-26 in FIG. 23.

The broken lines shown in the drawings are for illustrative purposes only, showing portions of the disposable diaper that form no part of the claimed design.
